UNITED STATES PATENT OFFICE.

CLARENCE E. REED, OF HOUSTON, TEXAS, ASSIGNOR TO REED ROLLER BIT COMPANY, OF HOUSTON, TEXAS, A CORPORATION OF TEXAS.

LUBRICATOR FOR DEEP-WELL-DRILLING APPARATUS.

Application filed January 13, 1923. Serial No. 612,481.

To all whom it may concern:

Be it known that I, CLARENCE E. REED, a citizen of the United States, and a resident of Houston, in the county of Harris and 5 State of Texas, have invented certain new and useful Improvements in Lubricators for Deep-Well-Drilling Apparatus, of which the following is a specification.

The invention relates to means for lubricating the bearings of the rotary cutters of 10 deep well drilling apparatus and includes the features and arrangements and combination of parts hereinafter described and particularly pointed out in the claims.

15 In the drawings:—

Fig. 1 is a central vertical section of the apparatus, excepting that at the plane of the lower cutters the section is taken along lines at right angles to each other, the right hand portion being taken through the side cutters, 20 while the left hand portion is shown in section along the axis of the cross roller cutters.

Fig. 2 is an enlarged sectional view of 25 parts of the cross roller cutter and its journal pin and showing an adjacent part of the cutter head and means for controlling the feed of lubricant.

Figs. 3 and 4 are sectional views showing a 30 train of gears for reducing the rate of movement of the piston in forcing the lubricant from its holder.

Fig. 5 illustrates enlarged the friction clutch arrangement shown also in Fig. 1.

The invention may be embodied in apparatus of different forms, and it is therefore to be understood that the form shown is illustrative of the principle of my invention and is not to be regarded as a limitation thereon, the scope of which is defined by the 40 appended claims.

In the drawings 1 is a part of the drill stem through which flushing fluid is forced 45 downwardly, by a pump on the drill rig platform for removing the detritus, which passes up between the drill stem and the wall of the well, after being dislodged by the cutters. These cutters may be of various forms and arrangements. They consist in the form chosen to illustrate my invention of side cutters 2, a cross roller cutter 3 and reaming cutters 7. The bearings of these cutters must be lubricated and for this purpose I show, as an example of my invention, a tube 4 arranged coaxially with the drill 50 stem and within the same, said tube being

screw threaded at its lower end onto a socket member 5 which in turn is screw threaded into some part of the drill head. In the instance illustrated this socket is screw threaded into the reamer block 6, which carries reaming cutters 7 for reaming out the well hole formed by the cutters at the lower end of the apparatus.

The flushing fluid passes down through the 60 drill stem and through the annular space 8 between the lubricant reservoir 4 and the drill stem, thence through ports 9 and conduit 10 in the socket member, from whence it is delivered through the central bore 11 of the reamer block to conduits 12 of the drill 65 head which deliver it to the recesses of the head in which the rotary cutters are located so that the cuttings or material cut or dislodged by the cutters will be carried up outside of the drill stem to be discharged from 70 the well.

The lubricant forced from the reservoir 4, as hereinafter described, passes through the 75 conduit 13 of the socket member 5 into the cup shaped space 14 at the upper end of the reamer block, thence through conduits 15 of the reamer block and through conduits 16 of the drill head 17 to the bearings of the 80 cutters 2 and 3, and distribution also takes place through conduits 18 to the bearings of 85 the reamer cutters.

The lubricant is forced from the holder 4 through the various ports by a piston 19.

A screw threaded rod or shaft 20 extends 90 lengthwise of the lubricating chamber and through the piston, which is correspondingly screw threaded. The shaft has its plain upper end bearing in a cap 22 which is screw threaded into the upper end of the lubricant holder. An extension of this shaft also bears in the coupling member 5 and there is a hydraulic packing at 23. The shaft is continued down through the water passages 10 and 11 and through the bit head at 24 and then on through the journal pin 25 of the cross roller cutter, as shown in Fig. 2, and if there is a cross brace in the lower recess of the head embracing this pin it will extend through this brace.

The lower end of the shaft is adapted to bear on the bottom of the hole, and in the example shown it bears at a point between the smaller sections 26 of the cross roller cutter or at the apex 27 of the bottom of 100 the hole. It will be understood that the 110

journal pin 25 is a fixed member supported in the walls of the head defining the central recess in the lower face of the head, in which recess the sections of the cross roller cutter lie.

Fig. 1 shows only about one-half of this pin, because the section at the left of the figure is at right angles to the plane of the section at the right of the figure. The pin 10 has a lubricant channel extending from each end portion to near the center, as at 28, and these channels receive lubricant from the channels 17 and deliver to the various roller sections through the ports 29. There are 15 supposed to be six roller sections in all, only three being shown in Fig. 1. The sections nearest the axial line of the drill are of the smallest diameter.

In the form of shaft shown in Fig. 1 it is 20 provided with a joint consisting of a socket portion 30 receiving the squared upper end 31 of the lower shaft section with a spring 32 interposed so that the lower section 20' may bear on the bottom of the hole, or 25 rather on the apex 27 with a yielding pressure.

The piston 19 has a packing 33 held by the section 34 pressed against it by a nut 35 by 30 which the packing is set in frictional contact with the wall of the lubricant holder 4 so as to rotate therewith as the whole apparatus is rotated. Other means may be provided to make the piston rotate with the whole apparatus, while allowing it to be moved 35 along the holder.

The spring 32 will cushion the shock of the contact of the shaft section 20' with the bottom of the hole, and by its pressure it will determine the strength of this contact.

0 In the operation of the apparatus the whole drill stem with the drill head is rotated in the well to perform the cutting operation and the lubricant holder and piston rotate with the apparatus. The screw rod does 45 not rotate in unison with the apparatus and thus the piston in turning around the screw rod will be advanced downwardly along the lubricant chamber to force the lubricant therefrom.

50 The screw will rotate but will lag in its rate of rotation in respect to the rate of rotation of the whole apparatus, the difference in these rates determining the rate that the piston will travel along the screw. The lag 55 of the screw is due to its contact with the bottom of the well.

The cap 22 may be provided with spaced apart projections to bear on the drill stem to 60 brace the upper end of the lubricant chamber without interfering with the downflow of the flushing fluid. Any suitable means may be employed to vent the upper end of the lubricant chamber to prevent the formation of a vacuum here as the piston is moved 65 down by rotating relative to the screw shaft.

A port may lead to the outside of the drill stem or into the interior of the drill stem. The screw threads are formed at a low pitch so that one revolution of the piston in respect thereto will move the piston along the 70 screw a very small distance. As shown in Figs. 3 and 4, reduction gearing may be interposed in the shafting which controls the screw threaded portion. This gearing may be located in the lower portion of the lubricant holding chamber where it is submerged 75 in the lubricant and is not subject to contact with the flushing fluid. It includes a plate 36 on the upper end of the lower section 20' of the shafting. The plate has a 80 pinion composed of an upper toothed section 37 of small diameter and a lower portion 38 of larger diameter, the latter meshing with a rack 39 fixed by a screw 44 to the casing 45 fixed at 45° to the lubricant chamber. 85 The upper smaller diameter portion of the pinion meshes with a gear member 40 which, like the plate 36, has a pin 41 about which a pinion 42 turns, the lower larger diameter toothed portion meshing with a fixed rack 90 43 and the upper smaller diameter toothed portion meshing with an internal rotary gear 46 connected to the screw shaft section 20. This reduction gearing gives a downward ratio equivalent to two inches per hour 95 of piston speed when the apparatus is running at 60 R. P. M.

In Fig. 5 is shown enlarged the friction clutch interposed between the upper and lower shaft sections 20, 20'. This mechanism of Fig. 5 is located in the lubricant chamber. The lower member 47 of the clutch has a squared hub 48 fitting in the squared socket 49 of the lower shaft section 20'. It is held on the lower end of the upper section of the shaft by a nut 50. The upper clutch member has a squared hub fitting a squared portion 51 of the upper shaft section, and it is pressed into engagement with the lower friction member by a spring 52, the tension of which can be set by a nut 53 and jam nut 54.

100 In this construction rotation of the lower shaft section is retarded or resisted by contact with the bottom of the hole, and slippage occurs at the friction clutches in accordance with the adjustment of the spring 52, and this slippage in connection with whatever degree of retardation takes place 110 at the lower shaft section determines the movement of the screw shaft section 20 in relation to the rate of rotation of the piston.

If the screw shaft lags very little, then 115 there will be a very slow downward movement of the piston and a very slow feed of the lubricant, so that the supply of lubricant will last for a considerable period of drilling, this rendering it unnecessary to remove the apparatus from the well for refilling of 120 the lubricant chamber for a long time.

In this refilling operation the cap 22 and the piston would be removed. The screw shaft could remain in place.

The spring cushion may be used in all the forms shown.

It will be understood that I do not limit myself to the use of the friction clutch shown in Figs. 1 and 5, nor to the reduction gearing between the shaft sections.

10 I claim:

1. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod having an extension coaxial with the apparatus and bearing at the center of the bottom of the hole being drilled, said extension holding the screw rod against rotating in unison with the rotation of the whole apparatus together with the piston whereby said piston is advanced along the screw rod, substantially as described.

2. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod having an extension coaxial with the apparatus and bearing at the center of the bottom of the hole being drilled, said extension holding the screw rod against rotating in unison with the rotation of the whole apparatus together with the piston whereby said piston is advanced along the screw rod, said extension and screw rod having relative movement and a connection between them permitting said relative movement, substantially as described.

3. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod having an extension coaxial with the apparatus and bearing at the center of the bottom of the hole being drilled, said extension holding the screw rod against rotating in unison with the rotation of the whole apparatus together with the piston whereby said piston is advanced along the

screw rod, and a spring cushion pressing said extension downwardly.

4. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod 70 having an extension coaxial with the apparatus and bearing at the center of the bottom of the hole being drilled, said extension holding the screw rod against rotating in unison with the rotation of the whole apparatus together with the piston whereby said piston is advanced along the screw rod, and means interposed between the extension and screw rod whereby these have relative rotary movement.

5. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod having an extension coaxial with the apparatus and bearing at the center of the bottom of the hole being drilled, said extension holding the screw rod against rotating in unison with the rotation of the whole apparatus together with the piston whereby said piston is advanced along the screw rod, and a friction clutch connection between the screw rod and its extension, substantially as described.

6. In rotary deep well drilling apparatus the combination of a drill stem, a head carrying cutters, a lubricant chamber with conduits leading to the cutter bearings, a piston in the chamber for forcing the lubricant to the cutter bearings, a screw threaded rod extending lengthwise of the lubricant chamber and through the piston, said screw rod having an extension coaxial with the apparatus and bearing at the center of the bottom of the hole being drilled, said extension holding the screw rod against rotating in unison with the rotation of the whole apparatus together with the piston whereby said piston is advanced along the screw rod, a spring and slip joint connection between the screw rod and its extension and means for adjusting the spring.

In testimony whereof, I affix my signature:

CLARENCE E. REED.
